UNITED STATES PATENT OFFICE

ARTHUR CLAUD-MANTLE, OF BRIDGEPORT, CONNECTICUT, ASSIGNOR TO THE BASICK COMPANY, OF BRIDGEPORT, CONNECTICUT, A CORPORATION OF CONNECTICUT

DESIGN FOR A HANDLE FOR AUTOMOBILE HOOD CATCH

Application filed July 18, 1928. Serial No. 27,520. Term of patent 14 years.

To all whom it may concern:

Be it known that I, ARTHUR CLAUD-MANTLE, a citizen of the United States, residing at Bridgeport, in the county of Fairfield and State of Connecticut, have invented a new, original, and ornamental Design for a Handle for Automobile Hood Catch, of which the following is a specification, reference being had to the accompanying drawings, forming part thereof.

In the drawings:—

Fig. 1 is a side elevation of a handle for

automobile hood catch, showing my new design, the hood catch barrel being shown in dotted lines;

Fig. 2 is an inner end elevation; and

Fig. 3 is an outer end elevation.

I claim:—

The ornamental design for a handle for automobile hood catch, as shown.

Signed at Bridgeport, in the county of Fairfield, and State of Connecticut, this 9th day of July, 1928.

ARTHUR CLAUD-MANTLE.
